SAFETY LOCKS

Earl E. Welch, Madison, and Bernard P. Rosser, Covent Station, N.J., assignors to Wel-Kids, Inc., Madison, N.J., a corporation of Delaware

Filed May 31, 1966, Ser. No. 553,864

9 Claims. (Cl. 292—248)

ABSTRACT OF THE DISCLOSURE

A locking device adapted to be secured to a cabinet or other container to prevent children from opening the container. The lock has a pair of arms which are hinged together at one end. The arms are arranged in overlapping relation with each other. Each arm has a hole adjacent the free end of the arm and the holes may be aligned to receive a locking pin by swinging the arms into alignment. The arms are biased away from the aligned position. A clutch or locking member is mounted between the arms to prevent the arms from being moved into alignment. By manipulating the clutch which urges the arms into alignment, the arm holes may be brought into alignment, thereby permitting the arms to be separated from the locking pin. The locking pin is secured on one portion of the container and the arms are mounted on another portion, so that the locking device spans the container closure.

This invention relates to improvements in safety locks of the character used on various household containers, to prevent easy access thereto by children.

It has long been well known that children gain access to medicine cabinets, drawers, kitchen cupboards and the like, due to the simple and easy manner in which such access is usually available and thereby come into contact with medicines, detergents, sharp edged implements, and the like. Danger and injury to such children is often the result of such easy access.

Key locks for such containers that would exclude children from access thereto would also present problems of having the appropriate keys available when a householder or adult wants to gain access thereto, and yet no effective means has been provided heretofore for preventing the access by children without serious interference with the availability of access to adults and other responsible persons.

One object of this invention is to overcome these objections and to provide for effective closing of containers against ready access by children while permitting of easy access from grown-ups and other responsible persons.

Another object of the invention is to improve the construction of locks to prevent the simple opening thereof except on multiple manipulations, such for example as with different hands, whereby these may not be readily released by children.

These objects may be accomplished, according to one embodiment of the invention, by providing a clasp having two overlapping arms which are joined together at one end for relative swinging movement and may be connected with one part of the cabinet or container. Each of the arms has a hole approximately at the center thereof, adapted to be brought into alignment upon relative swinging motion of the arms with respect to each other. A locking member is positioned between the arms, with a U-shaped slot for receiving pins projecting inwardly from the arms.

The U-shaped member normally would prevent relative swinging motion of the arms and yet, when this member is manipulated, the arms are readily moved relative thereto, to release a pin engaged in the aligned openings. This pin may be connected with another removable part of the

2

container, such for example as the drawer of a cabinet. The compound motion requires separate manipulation of two elements, which makes the clasp readily releasable by an adult or other responsible person and yet could not be readily opened by a small child.

This embodiment of the invention is illustrated in the accompanying drawings, in which:

FIG. 1 is a front elevation of a cabinet device, showing the lock applied thereto;

FIG. 2 is a view at right angles to FIG. 1;

FIG. 3 is a front elevation of the clasp structure in position for releasing;

FIG. 4 is a similar view in the locked position;

FIG. 5 is a transverse sectional view on the line 5—5

in FIG. 6;

FIG. 6 is an end elevation thereof;

FIG. 7 is a cross section on the line 7—7 in FIG. 5;

FIG. 8 is a perspective view of one of the arms detached;

FIG. 9 is a perspective view of the lock member detached; and

FIG. 10 is a longitudinal sectional view through a clasp, showing modifications therein.

The invention is shown in FIGS. 1 and 2 as applied to a cabinet, generally indicated by the numeral 1, and which has a drawer 2 slidably mounted within the body portion of the cabinet, capable of being withdrawn relative thereto. Provision is made for locking the drawer 2 against ready withdrawal or release from the cabinet 1 and yet to permit of release thereof when the lock is released by an adult.

In the illustrated embodiment of this invention, a clasp is illustrated generally at 3, being supported on a strap or other suitable support 4, mounted at 5 on the front portion of the cabinet 1. The clasp 3 is adapted for locking connection with the drawer 2 by means of a pin 6 supported on a strap or other suitable means, indicated at 7, attached in a suitable manner, as by a fastening 8, to the front of the drawer 2. Thus, when the clasp 3 is in locking engagement with the pin 6, as shown in FIGS. 3 and 4, the drawer 2 cannot be opened, but this safety lock is capable of ready release by an adult or other responsible person.

The clasp 3 comprises a pair of upper and lower arms 9 and 10, one end of which is pivoted at 11. The pivot 11 may also serve to connect the arms 9 and 10 to the strap or fastening device 4. The arms 9 and 10 are in the form of elongated plates inverted in face-to-face relation.

As stated, these plates are pivotally connected at one end 11. At the opposite end of each plate is provided a guiding hook 12 extending transversely and having an offset hook portion 13 spaced from the adjacent face of the plate forming the arm a distance sufficient to receive under the hook 13 an edge portion of the other coating plate. A recess 14 is formed in this edge portion, within which the hook 13 is received, so as to insure of the maintenance of proper alignment of the end portions of the plates 9 and 10 as these plates swing transversely relative to each other in the manner shown in FIGS. 3 and 4.

Grooves 15 are formed in the opposing faces of the respective plates 9 and 10, having longitudinally extending shoulders 16 in the transversely opposed portions of the respective arms 9 and 10. A leaf spring 17, in the form of a bowed spring, is received in the channel 15, with the ends of this leaf spring bearing upon the shoulders 16 normally tending to separate the arms, swinging them laterally relative to each other, as illustrated in FIG. 4.

Each of the arms 9 and 10 has a hole 18 therethrough, located approximately midway of the width of the arm and with an offset portion 19 at one side of the hole 18 in position to be aligned with a similar offset or notched

portion 19 of the other arm when these are moved apart by the action of the spring 17, as shown in FIG. 4. This is the locked position.

The holes 18 receive therethrough the pin 6, and when the arms are spread apart, as shown in FIG. 4, the pin is incapable of being withdrawn from the openings because the head 6' is larger than the diameter of the aligned recesses 19 in this position of the device. However, when the arms are pressed together, as shown in FIG. 3, the holes 18 are aligned and these are of sufficiently large diameter relative to the head 6' that the pin and its head can be withdrawn readily from these aligned holes 18.

The lateral pressure on the two arms may be applied by pressing inward on the edges of the arms. However, to facilitate such pressure, the arms may be provided, if desired, with plates or thumb press members, generally indicated at 20. One of these plates 20 is attached to a lateral edge of each of the arms 9 and 10, according to the illustrated embodiment of the invention.

A lock member, generally indicated at 21, is slidably received between the shoulders 16 on the inner faces of the opposed plates forming the arms 9 and 10. This lock member 21 normally is urged outward by suitable spring means, such as leaf springs 22, bearing against the inner end of the lock member.

Each of the leaf springs 22 is anchored at its outer end in a slot 23 formed in a lateral portion of one of the plates forming the arms 9 and 10. The outer end of the lock member 21 is provided with a thumb press portion, generally indicated at 24. This portion 24 is externally of the end of the arms 9 and 10 and may be formed as a small plate attached to the adjacent end of the lock member 21, as for example by being cast or otherwise formed integral therewith.

The lock member 21 has a U-shaped slot 25 formed therein and which receives a pair of lugs 26 formed as abutments or projections on the inner faces of the plates, comprising the arms 9 and 10. These abutments 26 should be so positioned with respect to the arms that they will be brought substantially into abutting relation when the arms are moved inward to their releasing position, as shown in FIGS. 3 and 5, in which position they will be located approximately midway of the length of the U-shaped slot 25 in the straight base portion of that slot.

However, when the arms 9 and 10 are released, they will be spread apart by the leaf spring 17, which action will cause the lugs 26 to move outward in the slot 25 to the ends of the latter, and the lock member 21 then will be pushed lengthwise of the arms 9 and 10 by the springs 22 to dispose the lugs 26 in the end portions of the U-shaped slot 25, as shown in FIG. 4.

This will make it impossible for the clasp to be released until the lock member 21 has been manually pushed inward and held in its inward position while the arms 9 and 10 are moved inward to the position shown in FIG. 3. This compound movement is difficult for performance by an untrained child, but is readily apparent to an adult or other responsible person who can easily release the locking device.

The operation and use of the safety lock will be apparent from the foregoing explanation. When applied to a cabinet or other container, it may be used to maintain the latter in closed relation until suitable precautions are observed for release of the contents. This safety lock may be applied to drawers, closures or other fastening devices to prevent children from gaining access to medicine cabinets, kitchen cupboards and other containers where injury may result therefrom. At the same time, it can be easily and readily released by a compound motion of an adult without requiring a key or complicated releasing action.

The invention is shown in a modified form in FIG. 10, wherein the pair of arms indicated at 29 and 30 are urged apart by a coiled spring 31 housed within aligned openings 32 in opposed portions of the plates forming the arms. In this form also the thumb press members, indicated

at 34, are secured to the edge portions of the respective arm portions 29 and 30 by pins 33.

Thus, separate plates may be used and easily applied to the edge portions of the respective arms to form the thumb press portions for manipulating the arms. In other respects, this form of the invention is constructed and operates in the manner described above with respect to FIGS. 1 to 9.

While the invention has been illustrated and described in certain embodiments, it is recognized that variations and changes may be made therein without departing from the invention as set forth in the claims.

We claim:

1. A safety lock comprising a pair of members adapted to be connected with one part to be latched, said members being hinged together adjacent one end on a common pivot, said members being movable in a lateral direction relative to each other between first and second lateral positions, a pin adapted to be connected with a second part, means for retaining said pin in secure engagement with the pair of members upon relative lateral movement of said members to said first position, said retaining means releasing said pin from engagement with said members upon relative lateral movement of said members to said second position, and a lock member adjacent the opposite end of said members for preventing movement of the pair of members from said first to said second positions, said lock members being movable relative to the pair of members in a direction substantially perpendicular to said lateral direction between a locked position and an unlocked position, abutment means on said members in position for cooperating with said lock member in said locked position to prevent said lateral movement of said members and in said unlocked position to allow said lateral movement, and means yieldably urging said lock member toward said locked position.
2. A safety lock according to claim 1, wherein the retaining means includes aligned holes through the pair of members for slidably receiving the pin therein.
3. A safety lock according to claim 1, wherein the retaining means includes aligned holes through the pair of members for slidably receiving the pin and with offset portions of the holes in complementary relation when the members are moved to said first position relative to each other, and means on the pin for preventing withdrawal of the pin when the members are in the first position.
4. A safety lock according to claim 1, including spring means interposed between the members biasing said members toward said first position, said members each having an outer lateral edge, said lateral edge of one member being on the opposite side of said retaining means from the lateral edge of the other member, said lock member being spaced a greater distance from said retaining means when in said locked position than when in said unlocked position, whereby said member lateral edges and said lock member are moved toward said retaining means in releasing said pin from said members.
5. A safety lock according to claim 1, wherein the pair of members comprises a pair of plate-like structures in face-to-face relation.
6. A safety lock comprising a pair of members adapted to be connected with one part to be latched, a pin adapted to be connected with a second part, means for interconnecting said pin with the pair of members, and a lock member for preventing withdrawal of the pin from the pair of members, said lock member being manually movable jointly with the pair of members to release the pin from interconnected relation with the pair of members, said lock member having an angular slot therein, and said pair of members having portions projecting into the slot for controlling relative movement therebetween.
7. A safety lock comprising a pair of members adapted to be connected with one part to be latched, a pin adapted to be connected with a second part, means for interconnecting said pin with the pair of members, and a lock

member for preventing withdrawal of the pin from the pair of members, said lock member being normally movable jointly with the pair of members to release the pin from interconnected relation with the pair of members, said lock member being slidably lengthwise of the members and having a U-shaped slot therein, pins carried by the respective members and extending into the slot in positions to control relative motions between the lock members and the pair of members.

8. A safety lock comprising a pair of members arranged in face-to-face relation, means pivotally connecting the members together at one end, said members having aligned openings therein, a pin extending through the aligned openings and detachable therefrom in one position of the members, means yieldably urging the members apart to prevent removal of the pin, a lock member slidably mounted between the pair of members in guided relation toward and from the pivot, means yieldably urging the lock member in one direction, said lock member having a U-shaped slot therein, lugs on the respective members

extending into the slot in positions to control movement of the members, said pair of members and lock member having handles thereon for respective movements substantially at right angles to each other.

5 9. A safety lock according to claim 8, including means for connecting the pair of members together.
